UNITED STATES PATENT OFFICE.

FREDERICK MARTEN HALE, OF CATFORD, ENGLAND.

EXPLOSIVE-SHELL.

No. 926,558.

Specification of Letters Patent.

Patented June 29, 1909.

Application filed April 18, 1908. Serial No. 427,846.

To all whom it may concern:

Be it known that I, FREDERICK MARTEN HALE, a subject of the King of Great Britain, residing at Catford, England, have invented 5 certain new and useful Improvements in Explosive Shells, of which the following is a specification.

The object of my invention is to so construct a fuse for explosive shells, of simple 10 mechanism, which shall avoid the possibility of coming into action in the gun on shock of discharge; impact with an armor plate, or other obstruction being necessary to fire it, so that an effective delay is created 15 after the impact of the shell before the explosion takes place, thus allowing the explosion of the shell to take place after piercing, and in or behind the armor or object struck. Should the detonator prematurely fire in the 20 gun or during transit, or otherwise, the flash or flame is retained within the fuse, and does not communicate with the explosive bursting charge, thus rendering the fused shell safe to fire or handle under practically any condition. 25

My invention will be clearly understood from the following description aided by the accompanying drawings in which:—

Figure 1 is a sectional elevation of a fuse 30 constructed in accordance with the present invention. Fig. 2 is a sectional elevation in a plane at a right angle to the plane of Fig. 1.

The body of the fuse is shown at A and is 35 in the form of a hollow plug having a bore C extending from its outer end and having a bore of less diameter extending from the bore C to the inner end of the plug. In the larger bore is arranged a hammer F' having an axial tubular extension T which is disposed 40 in the smaller bore for axial sliding movement. The extension T is held normally against movement by spring pressed bolts V, the ends of which are normally held in recesses in the plug A. The outer end of the 45 latter is closed by a plug I which also retains the hammer F' in position.

The end of the body A is closed by a frangible disk-like section Q which may be integral with or otherwise rigidly secured to the material of the body. The section Q prevents 50 the flash of the flame from reaching the explosive material in case the detonator is prematurely fired.

The detonator, indicated by the numeral 55 D is located at the end of the extension T in alinement with the bore B of said extension

and also in alinement with the bore of a hollow punch S which is secured in the end of the extension T and engages the frangible section Q at the point R to sever said section 60 prior to the firing of the detonator in order that the flash of the latter may reach the explosive material.

Cooperating with the detonator is a needle pellet F which is disposed in a central bore of 65 the hammer F' and has a transverse recess through which the bolts V project. The pellet F is held normally against movement with relation to said hammer by any suitable means, as for example, a frangible shearing 70 pin G'.

In action, the bolts V are disengaged from the body A by centrifugal force, leaving the hammer F' free to move to the end of the bore C, which movement takes place as a result of the impact of the shell. This movement of the hammer is preliminary to the movement of the needle pellet and produces the breaking of the section Q. The needle pellet is then projected along the bore B, the 75 pin G' having broken, and fires the detonator. It is apparent that this firing takes place after the action of the hammer in severing the section Q.

What I do claim and desire to secure by 80 Letters Patent is:—

1. In a fuse for explosive shells, in combination, a body having an axial bore, a detonator at one end of the bore, a needle pellet and needle carried thereby at the other end 90 of the bore, means for holding the needle pellet normally against forward movement, said means being operable to release the needle pellet whereby the latter has forward movement, upon the retardation of the 95 movement of the shell, means closing the end of the bore for retaining the flash of flame from the detonator, should the latter have premature explosion, and means for moving said last named means from the end of the 100 bore prior to the action of the detonator when fired by the needle pellet.

2. In a fuse for explosive shells, in combination, a body having an axial bore, frangible means closing one end thereof, a detonator 105 arranged in said bore, movable needle means for firing the detonator, means normally holding the needle means against movement and operable to release the latter upon the retardation of the movement of the shell, 110 punch means for severing said frangible means, hammer means associated with the 115

punch means and causing the latter to have operation prior to the firing of the detonator by said needle means, and means for holding said hammer means normally against active 5 movement and operable by the transmitted influence of the force of movement of the shell to release said hammer means.

3. In a fuse for explosive shells, in combination, a body having an axial bore, frangible means closing one end thereof, hammer means movable in the bore, a punch carried by said hammer means to sever said frangible means, bolts normally held engaged with said body and operable by centrifugal action 10 to release said hammer means, the latter also having an axial bore, a detonator in said last named bore, needle means in said last named bore and movable to fire the detonator, and frangible means for holding said needle 15 means normally against movement.

4. In a fuse for explosive shells, in combination, a body, having a frangible closed end, detonator means in the body, needle pellet means for firing the detonator means, means 20 normally holding the needle pellet means against movement and permitting the movement of the needle pellet means as a result of impact, punch means for breaking the

frangible closed end of the body and operable preliminarily to the action of the needle 30 pellet means and means normally holding the punch means against operation and permitting the operation thereof as a result of impact.

5. In a fuse for explosive shells, in combination, a body, frangible means closing the end thereof, punch means for severing the frangible means, the punch means and the frangible means being relatively movable, detonator means, means for firing the detonator 35 means after the operation of the punch means, means normally preventing the operation of the detonator firing means and operable as a result of impact to allow of such 40 operation and means normally preventing the operation of the punch means and operable as a result of impact to allow of such 45 operation preliminarily to the operation of the firing means.

In testimony whereof I have hereunto set 50 my hand in presence of two subscribing witnesses.

FREDERICK MARTEN HALE.
